UNITED STATES PATENT OFFICE.

PETER D. THROPP, OF TRENTON, NEW JERSEY, ASSIGNOR TO THE DE LASKI & THROPP CIRCULAR WOVEN TIRE COMPANY, OF TRENTON, NEW JERSEY, A CORPORATION OF NEW JERSEY.

VULCANIZING-MOLD.

1,082,373.

Specification of Letters Patent. Patented Dec. 23, 1913.

Application filed March 20, 1911. Serial No. 615,521.

To all whom it may concern:

Be it known that I, PETER D. THROPP, a citizen of the United States, and resident of Trenton, in the county of Mercer and State 5 of New Jersey, have invented a new and useful Improvement in Vulcanizing-Molds, of which the following is a specification.

This invention relates to a vulcanizing mold for repairing the outer casings of 10 pneumatic tires and like articles, and has for one of its objects to provide a device of this character which is assembled in a portable unit.

Another object is to provide apparatus 15 of this character which is adapted to utilize vulcanizing mold members of various sizes, in order that repairs may be made on different sized casings and different characters of injuries to be repaired.

20 A further object is to provide means for adequately supporting and confining the portion of the casing being vulcanized, while the device itself provides sufficient pressure during vulcanization without the aid of any 25 mechanical means for increasing the pressure.

A further object is to provide a device of 30 this character which may be very quickly and conveniently manipulated, and a still 35 further object is to provide certain improvements in form, construction and arrangement of the various parts whereby the above mentioned objects and other objects incident to the nature of the device may be effectively carried out.

One practical embodiment of the invention is represented in the accompanying drawings, in which,

Figure 1 represents a top plan view of the 40 device. Fig. 2 represents a side elevation of the same. Fig. 3 represents a front elevation, parts being broken away, and Fig. 4 a vertical section.

A standard or upright supporting post is 45 denoted by 1, and is provided with an enlarged base 2 and a reduced upper portion 3. This standard 1 is preferably made hollow and skeleton in form for the purpose of lightness. A pair of arms 4, 5, are mounted one above the other on the reduced por-

tion 3, and are fitted to swing thereon in a horizontal direction. These arms 4 and 5 are bent, as clearly shown in Fig. 3, so that their outer ends lie in the same plane and consequently are fitted to swing toward and away from each other in the same horizontal plane. A pair of set screws 6 are screw-threaded in the arms 4 and 5, and fitted to engage the reduced portion 3 of the standard 1, for temporarily securing the arms 4 55 and 5 in any desired position.

The outer ends of the arms 4 and 5 are provided with vertical openings in which are rotatably mounted two sets of clamping jaws, one for each arm. These jaws each 65 comprise a main member 7 and an auxiliary member 8 adapted to slide and swing, the latter on the former, toward and away from each other. A pair of screw bolts 9, 10, are mounted one in each member 7, 8, of each set 70 of jaws; the bolt 9 being screw-threaded in the jaw 7 and having its end fitted in the jaw 8, which end is reduced as shown in dotted lines in Fig. 4, so as to form a shoulder on the bolt 9 against which the lower portion 75 of the jaw 8 will abut to prevent it from sliding toward the jaw 7. The bolt 10 is rotatably mounted in the jaw 8, and its end is screw-threaded in the jaw 7. By virtue 80 of this arrangement of the two screw bolts 9 and 10, the upper ends of the jaws 7, 8, may be swung toward and away from each other by manipulating the two screw bolts 9 and 10 as follows: The screw bolt 9 will be set so as to allow the lower portion of the 85 jaw 8 to be in such proximity to the upright portion of the jaw 7, as the thickness of the article to be gripped requires. The article to be gripped may then be inserted between the upper ends of the jaws 7, 8, and the 90 screw bolt 10 tightened up, thus swinging the upper extremities of the jaws toward each other and into tight pinching engagement with the article therebetween.

The vulcanizing mold proper comprises a 95 core member 11, which is shown in the present case as being in general of the shape of a segment of a circle. This core 11 may be hollow and be provided with plates 12, for closing the ends thereof, which plates are 100

secured to the core by screw bolts 13. Making the core 11 hollow, provides for a steam chamber therein, which steam chamber is shown as having its wall parallel in longitudinal and cross section with the outer surface of the core for providing equal heat at all portions of the surface of the core. This core member 11 is also provided with depending lugs 11* fitted to engage the clamping jaws 7, 8, for supporting the vulcanizing mold. The vulcanizing mold also comprises a bead molding member constituted by two side pressure plates, or mold sections, 14, fitted to abut one against each side of the inwardly extending tongue 15 of the core 11; which plates 14 may be held in abutting engagement with the core 11 by means of screw bolts 16 passing through both plates and the tongue 15. These side pressure plates are fitted to engage the marginal portions of a tire casing and are shown as extending about half way up the sides thereof, and terminating in relatively thin outer edges. They are also shown in the drawings as being adapted to engage the marginal portions of that form of tire casing known as a "clencher" casing, but it will be understood that this particular form of the inner faces of the plates 14 is not an essential of the invention. The vulcanizing mold further comprises a tread molding member 17 substantially semi-circular in cross section, which is fitted to engage and rest upon the outer body portion of the tire casing during vulcanization, and extend far enough down to overlap the outer edges of the side pressure plates 14, so as to provide, together with the said plates, a complete inclosure for that section of the casing being repaired. This member 17 is provided with a steam chamber 18, which is shown as extending substantially from end to end thereof, and as having its inner and outer walls parallel in both longitudinal and cross section, thereby providing equal vulcanizing heat throughout the whole operative face of the member. The standard 1 is provided with a pair of brackets 19, for supporting the main steam feed pipe 20. This pipe 20 is provided at its top with a cross-head 21 tapped to receive the ends of branch supply pipes 22, 23, the other ends of which pipes are tapped into the core proper 11, as shown at 24, Fig. 2, and the tread vulcanizing mold member 17, as shown at 25, Fig. 4, respectively. The ends of the core member 11 and vulcanizing mold member 17, opposite the ends connected with the supply pipes, are provided with exhaust steam pipes 26 and 27 respectively. The branch supply pipes 22, 23, may be provided with valves 28, and the exhaust steam pipes 26, 27, with valves 29. The fact that the inlet and exhaust pipes are tapped into

opposite ends of each member requires the steam to pass throughout the steam chamber 65 in each member before it is exhausted. The main feed pipe 20 may be connected at its lower end with any convenient source of live steam supply.

The tread vulcanizing mold member 17 is 70 centrally provided with a screw eye 30 adapted to engage the hook of a tackle, not shown, for convenient raising and lowering of this member when in use.

In operation, a core member of the proper 75 section and length for making the desired repair is secured into the clamping jaws 7, 8, by clamping the lugs 11* between the said jaws, the fact that the arms 4, 5 are adjustable permitting them to support any desired 80 length of core. The tire casing to be repaired is hung on the core member 11 with the injured part on the core itself. After the injured part has been properly treated preparatory to vulcanization, the side pressure plates 14 are clamped in position on the tongue 15, thus securing the tire on the core 11, and the tread vulcanizing mold member 17 is lowered into position on the outer body portion of the tire casing, as clearly shown 90 in Figs. 3 and 4. Live steam is then admitted to the steam chambers of the core 11 and member 17, and the action is continued until the proper vulcanization has been effected. The introduction of steam may then be discontinued and the member 17 lifted from the tire, the pressure plates 14 removed therefrom and the tire removed from the apparatus.

It will be seen that this device is arranged to receive, as mentioned above, vulcanizing molds of various cross sections and lengths, and that its manner of use is extremely effective, the weight of the member 17 itself being sufficient to provide the necessary 105 pressure over the outer body portion of the tire during vulcanization, while the side pressure plates 14 sufficiently confine the marginal portions of the casing.

It is to be understood that various changes 110 may be resorted to in the form, construction and arrangement of the several parts without departing from the spirit and scope of my invention; hence I do not wish to limit myself strictly to the form herein shown and described, but

What I claim is:

1. Apparatus of the character described comprising a core, bead and tread mold members, lugs depending from said core, a 120 support, and means carried by said support fitted to engage the lugs for supporting the core and mold members.

2. Apparatus of the character described comprising a mold including a core, lugs 125 depending therefrom, a support having a

pair of arms fitted to swing toward and away from each other, and means rotatably mounted in the outer ends of the said arms to engage the said lugs for supporting the core and mold.

In testimony, that I claim the foregoing as my invention, I have signed my name in

presence of two witnesses, this 16th day of March 1911.

PETER D. THROPP.
